UNITED STATES PATENT OFFICE.

FREDERICK W. KING, OF CLEVELAND, OHIO.

DESIGN FOR SPECTACLES.

45,424.

Specification for Design.

Patented Mar. 17, 1914.

Application filed November 25, 1912. Serial No. 733,537. Term of patent 7 years.

To all whom it may concern:

Be it known that I, FREDERICK W. KING, a citizen of the United States, residing in Cleveland, in the county of Cuyahoga and State of Ohio, have invented a new, original, and ornamental Design for Spectacles, of which the following is a specification, reference being had to the accompanying drawing, forming a part thereof.

The figure of the drawing is a perspec-

tive view of a pair of spectacles showing my new design.

I claim:

The ornamental design for spectacles substantially as shown.

FREDERICK W. KING.
